SPRING CUSHION ASSEMBLY

Murray J. Rymland, Baltimore, Md.

Application October 8, 1953, Serial No. 384,874

2 Claims. (Cl. 5—275)

This invention relates to spring cushion assemblies, and more particularly to spring assemblies of the type including a large number of helical coil springs associated and interconnected in predetermined spaced relation to each other. Assemblies of this type are described in my prior Patent No. 2,630,586, granted March 10, 1953, and the present invention represents a variation and improvement of the structure therein claimed.

Among the general objects of the present invention are to provide a spring cushion assembly adapted to distribute applied pressure smoothly and evenly, and to provide an assembly of simplified, durable and inexpensive construction, wherein lateral displacement of component coil springs is effectively prevented.

A particular object of the invention is to provide a spring cushion assembly employing elongated metal straps to secure the rows of springs, whereby the overall assembly is effectively stiffened, and the length of each spring row is positively established and maintained.

Another object is to provide a spring cushion unit adapted for semi-automatic and automatic assembly.

A further object is to provide a spring cushion assembly adapted to prevent padding or filling material from entering into the component springs thereof, when utilized in mattresses, upholstered furniture or the like. Further objects of the invention will be in part obvious and in part pointed out hereinafter.

The invention and the novel features thereof may best be made clear from the following description and the accompanying drawings, in which:

Figure 1 is a fragmentary plan view of a spring cushion assembly constructed according to the present invention;

Figure 2 is an elevational view of the cushion assembly section illustrated in Figure 1;

Figure 3 is an enlarged view taken on the line 3—3 of Figure 1, looking toward an end of the novel securing strap;

Figure 4 is a sectional view on the line 4—4 of Figure 3;

Figure 5 is an enlarged sectional view taken on the line 5—5 of Figure 1;

Figure 6 is an enlarged sectional view taken on the line 6—6 of Figure 1, and

Figure 7 is an enlarged sectional view taken on the line 7—7 of Figure 1.

Referring to the drawings in detail, the spring cushion assembly comprises a plurality of component helical coil springs 10, constructed of wire in conventional form as illustrated in Figures 1 and 2. Each row of springs is aligned and arranged with an arcuate portion of the end convolution of each spring overlapping a corresponding portion of an adjacent spring in the same row, whereby one such portion becomes an overlying arcuate portion 11 and the other an underlying arcuate portion 12, and a space 13 is provided between the overlapping portions.

To fix adjacent rows in desired parallel spaced relationship, a plurality of tie wires 14 extend transversely of the rows along the lines of overlap between the coils.

2

Each tie wire 14 is provided with a plurality of pairs of spaced depressions 15, each pair of depressions being separated by an upwardly projecting insert 16 therebetween, as best illustrated in Figures 3 and 7. When positioned in the assembly, each pair of depressions 15 partially embraces the intersecting sections 17 of an overlapping pair of arcuate portions 11 and 12, and the intermediate insert 16 projects into the space 13 therebetween. As will be readily understood, the pairs of depressions 15 are spaced along the length of tie wires 14 to suitably space from each other adjacent rows of component springs, the structure illustrated in Figure 1 being merely a partial view of one spring row of the overall assembly.

In my prior patent referred to, the overlapping arcuate portions of adjacent springs in a row are secured to each other and to the tie wire inserts by individual clamp members firmly engaged to those elements. While such structural relationship is entirely satisfactory, I have now discovered that for some applications further advantages reside in employing along each row of springs elongated metal straps 18 of substantial width, arranged to pass under the insert of each tie wire and over the overlapping arcuate portions of the springs. Each strap 18 extends the length of a spring row, replacing accordingly a plurality of individual clamp members.

The strap 18 underlying inserts 16 of the tie wires and overlying the overlapping arcuate portions 11 and 12 of the individual springs effectively retains the intersecting sections 17 of the arcuate portions in the depressions 15 of the tie wires, whereby lateral movement of the springs relative to each other or axially of the tie wires is effectively prevented. This locking function of the strap is illustrated in Figure 5. To similarly prevent lateral displacement of the springs in the direction of the row, each strap may be permanently and reversely crimped at suitable intervals, to form therein humps 19 adapted to underlie and partially enclose the tie wire inserts, and adjacent humps 20 adapted to overlie and partially enclose the adjacent overlying arcuate spring portion 11, see Figure 6. The crimps or humps 19, 20 are obviously spaced along the strap length to establish and maintain the desired position of each spring in the row. In this manner, the overall length of the spring row is positively established and firmly maintained.

Each end section 21 of the strap 18 may be reversely bent as at 22 (see Figures 3 and 4) about the end pair of arcuate portions 11 and 12 in the row, and permanently crimped to form a hump 23 partially enclosing the end underlying arcuate portion 12. In this manner, the relative position of each component spring of the row is permanently fixed, including the end springs thereof which are not traversed by the straps.

The straps, as will be readily understood, serve to effectively stiffen the overall assembly, particularly to resist endwise pressures exerted against the assembly in the row direction. The straps also establish and maintain the desired length and spacing of each spring row. Since they overlie the individual component springs, they also serve, when assembled in mattresses or furniture, to prevent the entry of padding or filling material into the interior of the coils. The latter function is enhanced by the substantial width of the straps. The flat strap configuration of the members 18 facilitates speedy and semi-automatic or automatic assembly of the units, since they may be readily positioned, either manually or mechanically, between the tie wires and the overlapping portions of the end convolutions of the springs in the process of assembly.

It will thus be seen that there has been provided by this invention a structure in which the various objects hereinbefore set forth, together with many practical ad-

vantages, are successfully achieved. As various possible embodiments may be made of the mechanical features of the above invention, all without departing from the scope thereof, it is to be understood that all matter hereinbefore set forth or shown in the accompanying drawings is to be interpreted as illustrative, and not in a limiting sense.

I claim:

1. A spring cushion assembly comprising a plurality of parallel rows of similar helical coil springs having their axes arranged in parallelism, each spring having an arcuate portion of an end convolution thereof so overlapping a corresponding portion of an adjacent spring in the same row as to provide a space between such overlapping portions, a plurality of tie wires extending transversely of the rows along the lines of overlap between the coils, each tie wire having a plurality of pairs of spaced depressions with upwardly projecting inserts therebetween, the depressions of each pair being disposed in embracing relation to the overlapping points of a pair of adjacent arcuate spring portions with the intermediate insert projecting into the space between said arcuate portions, and a metal strap of substantial width extending along each row under the intermediate insert of each tie wire and over the arcuate portions of said springs, said metal straps being humped to partially enclose each tie wire insert and each overlying arcuate spring portion, and the ends of said metal straps being reversely bent around the end pairs of adjacent arcuate portions in each row.

2. A spring cushion assembly comprising a plurality of parallel rows of similar helical coil springs having their axes arranged in parallelism, each spring having an arcu-

ate portion of an end convolution thereof so overlapping a corresponding portion of an adjacent spring in the same row as to provide a space between such overlapping portions, a plurality of tie wires extending transversely of the rows along the lines of overlap between the coils, each tie wire having a plurality of pairs of spaced depressions with upwardly projecting inserts therebetween, the depressions of each pair being disposed in embracing relation to the overlapping points of a pair of adjacent arcuate spring portions with the intermediate insert projecting into the space between said arcuate portions, and a metal strap of substantial width extending along each row under the intermediate insert of each tie wire and over the arcuate portions of said springs, said metal straps being in tight frictional engagement with each tie wire insert and with at least one of the corresponding arcuate portions of said springs to resist relative lateral movement between adjacent overlapping springs.
